ANDREW J. PEHL, OF SEATTLE, WASHINGTON, ASSIGNOR, BY MESNE ASSIGNMENTS, TO HENRY A. HEAVENS AND WILLIAM C. JEFFARES, BOTH OF SEATTLE, WASHINGTON

TRAVELING APPARATUS FOR RINSING AND DRYING RUGS

Application filed December 30, 1929. Serial No. 417,443.

This invention relates to an apparatus and process for distributing liquids, and for forcing liquids from fabrics, and particularly from rugs and carpets.

5 In the cleaning of large rugs and carpets, it is customary to apply to the goods a sufficient quantity of suitable liquids with soap or other cleansing chemicals to saturate the goods and to then scrub or otherwise treat the saturated goods till the dirt is driven therefrom or ready to be rinsed therefrom, and thereafter to force the liquids from the goods by running the same through, or between, large wringer rolls, similar in construction to 10 the ordinary clothes wringers of smaller proportions. But this manner of forcing out the liquids has been very unsatisfactory as it required the united efforts of several workmen to raise and guide the fabrics through the 15 rolls, and with the best care, the fabrics have frequently been wrinkled, pulled askew and the weave distorted, to the injury of the goods. And for rinsing the water has generally been applied manually by the work- 20 men.

It is therefore among the objects of this invention to provide an apparatus, or traveling wringer, for distributing liquids and rinsing water over the fabrics and particularly 25 to force the liquids from the fabrics as the same are rinsed and ready to be dried; and such work to be performed on the fabrics without moving the same, and by a single workman.

30 A further object of this invention is to provide a process or method of so cleaning, rinsing and drying the fabrics, while the same are spread out upon a flat surface, without moving the fabrics, by rolling over the goods 35 resiliént pressure roller.

With these and other objects as may hereinafter appear, I have illustrated my apparatus by the accompanying drawing, of 40 which:

Figure 1 is a top plan thereof;

Figure 2 is a front elevation in section taken on lines 2—2 of Figure 1;

Figure 3 is a view taken from one end; 45 and

Figure 4 is a cross section view taken on lines 4—4 of Figure 2.

Like numerals on the different figures represent like parts.

Numeral 5 represents a horizontal plat- 55 form or floor of any desired dimensions sufficient to permit the desired size of rugs or carpets to be spread out thereon for wet cleaning. The floor may be made of any suitable material, and cement has been found satisfactory. 6 shows any rug or fabric that 60 has been spread out on the floor for cleaning and drying.

7 illustrates a long round pressure roller placed across and over the fabric to be rolled, 65 for forcing the liquids therefrom. This roller may be tubular, but is preferably formed with a hard core and thick cover thereover of flexible material such as rubber for contacting with the fabric without injuring the 70 same and for receiving indents from any seams or ribs or other irregular thickness of the fabric, and so leave the remainder of the surface of the roller to press evenly on fabric as it is passed over the same. 75

Resting on the roller 7 and supported thereby are two parallel driving rolls 8 of substantially the same diameter, and extending the full length thereof, and rotatably held beneath a carriage, having side frames 9 and 80 10 and end frames 11 and 12. The rolls 8 straddle the roller 7 and impinge upon and turn the same, as the rolls are rotated as hereinafter shown, whereby the pressure roll 7 is rolled over and across the fabric and the liquid pressed therefrom by the weight of the 85 rolls and the carriage and load thereon.

13 is a deck built on the frame or carriage, whereon is mounted a reversible electric motor, 14, of any well known type. A drive 90 shaft 15 projects from the motor and through any suitable journal box 16, on the frame 12, and terminates beyond the same within a fixed driving pinion 17. This pinion meshes in a gear wheel 18 affixed on the end of a stub 95 shaft 19, which extends through the frame 12 and journaled on the deck at 20.

Affixed to the shaft 19 between the gear 18 and the frame, is a driving gear wheel 21 which meshes with and turns two similar 100

gear wheels 22 affixed to the ends of spindles 23 projected from the rolls 8. Similar spindles 24 project from the opposite ends of the rolls 8, and all turn freely in suitable journal bearings 25 affixed to the bottoms of the end frames 11 and 12.

It will thus be seen that as the motor turns the shaft 15, that the chain of gears will cause the rolls 8 to revolve in the same directions and so impinging on the pressure roll 7 on opposite sides thereof will cause the roll 7 to revolve or roll across the supporting platform and press the liquids out from the fabrics thereon spread. The rolls 8 are of iron or other heavy material preferably noncorrosive, and with sufficient rigidity to present an even pressure on the full length of the pressure roll, both for rotating the same and for holding the same evenly upon the surface to be pressed beneath.

A seat 26 is preferably erected upon the deck whereon the operator may ride, and additional weight is supplied to the carriage as may be needed by means of any suitable weights placed in a hopper 27 therefor on the deck.

In order to prevent the carriage from tipping to one side while being transported over and by the roll 7, the seat and weights in the hopper are placed slightly to one side of the roll 7, whereby the carriage normally extends to tip only toward that side, and extensions 28 from the end frames are provided with wheels 29 for supporting that side of the carriage and for guiding the carriage evenly across the platform and fabric.

And to assure the latter object, grooves or channel irons 30 are provided upon or embedded across the ends of the platform in which the wheels roll freely forward and back, but prevent any lateral or diagonal motion of the carriage by reason of square shanks on the posts 31 which extend from the wheels up through square holes in the extension frames 28. The posts are slidably positioned through the extensions, and helical springs 32 around the shanks between the lower faces of the extensions and the yokes 33 for the wheels tend to hold the wheels down into the grooves in cases where one corner of the carriage may be tilted and whereby one of the wheels would be lifted from the groove, except as held therein by the spring.

The reversible motor is provided with a shift lever 34, which may be used by the operator for reversing the motor to cause the carriage to move either forward or back accordingly as the lever is thrown in the direction desired, and is provided with a central or neutral position for disconnecting the impelling current.

There is also provided means for automatically reversing the direction of travel of the carriage as it reaches the desired limits for travel respectively as by a shift rod 35 pivot-

ed or yoked at its center to the shift lever with the rod slidably supported on a bracket 36, from the motor.

This rod is of approximately the same length as the width of the carriage, and when the lever is turned or thrown to either side, the respective end of the rod projects beyond the respective frame 9 or 10.

In order to supply any desired cleaning fluids to the fabric or rinsing water, thereto after being cleaned, I provide two suitable perforated pipes 37 along beneath the side frames connected centrally by pipes at the center, bent inward and upward as 38, 39 and attached respectively to opposite sides of any suitable three way valve of well known type indicated as 40, which is provided with a shift lever 41, and a hose bibb extension 42, whereon any flexible hose may be attached for supplying the desired liquid. By means of the shift lever 41 the operator may cause the liquid to flow alternately from either of the pipes 37 upon the fabric, or may cut off the flow to both, when it is desired only to force all liquid from the rug.

In order to raise the front side of carriage for any purpose, particularly for the removal of the roll 7, as for inserting another roller of different construction or length, for different sorts of material, I provide at the corners of the frame opposite the wheels, suitable elevator screw posts 43 which mesh with corresponding threads in holes through the frames. I also provide short levers 44 at the tops of the posts, whereby they may be turned and the lower ends thereof projected below the frames against the floor or platform till the frame and attached rolls 8 have been disconnected from the roll 7 or elevated above the same, whereupon the roll 7 may be easily removed.

While I have so shown one form of apparatus whereby the rugs and other fabrics may be cleaned, rinsed, and liquid pressed therefrom, yet I do not limit my invention to such particular form of apparatus, and further desire to claim particularly the method described, of spreading rugs, carpets and other fabrics on flat surfaces, and rolling thereover suitable flexible faced pressure rollers, and thereby pressing from such fabrics the liquid therefrom without moving the fabrics, and further the method of supplying to such fabrics while being so rolled any desired liquids for cleaning or rinsing the same.

In the art of cleaning, and particularly rinsing rugs, it is necessary that they be alternately wetted, or moistened, and then rolled or rung several times, in order to remove all dirt and cleansing matter therefrom; and my apparatus performs both functions together, as the rinsing water is applied from the pipes in advance of the drying roller behind, while the apparatus

crosses over the rug, any number of times required.

I have not shown any specific means of connecting the motor with circuit wires for electricity, but any ordinary attachments are used, and in some cases I use a rheostat in the line to enable the operator to control the current particularly when starting the motor. In other cases it is sometimes advisable to construct the driving shaft 15 in two sections and provide for the joining thereof by any ordinary clutch means, for regulating the speed of the driving pinion 17.

In practice it is also sometimes convenient to provide for the automatic shifting of the liquid lever 41 to alternately change the streams of water from one to the other of the pipes. Such shifting may be done by providing shifting means similar to that shown for automatically shifting the motor or reversing the same.

Additional means may also be provided for guiding the line of travel of the carriage, and I do not limit myself to such suggested additions.

Having described my invention I claim as new:

1. An apparatus for forcing liquids from wet fabrics, comprising a long pressure roller mounted over a rigid platform, and two parallel driving rollers mounted astride the pressure roller and supported thereby, for operating the pressure roller by frictional contact therewith and to roll the same over the platform, and means for driving the rollers.

2. An apparatus for pressing liquids from fabrics, comprising a frame, a long pressure roller positioned beneath said frame, two driving rollers rotatably mounted beneath the frame and in straddling position over the pressure roller and means for rotating the driving rollers for rolling the pressure roll over a wet fabric on a fixed surface.

3. An apparatus for removing liquids from wet carpet rugs, comprising a movable carriage, two driving rolls rotatably mounted beneath the carriage, a pressure roller beneath the driving rolls and operated thereby, means carried by the carriage for turning the driving rolls whereby the pressure roll is rotated along beneath the carriage while supporting the same, over the rug.

4. An apparatus for forcing liquids from carpet rugs while spread over a fixed platform, comprising, a pressure roller, a movable carriage supported by said pressure roller, a reversible motor affixed to the carriage and operatively connected with the pressure roller for rotating the same and to thereby move the carriage over the platform, and a lever operatively connected with the motor for reversing the same.

5. An apparatus for pressing liquids from a carpet rug and for simultaneously rinsing the same comprising an elongated pressure

roller, a movable carriage, two driving rolls rotatably attached to the carriage and held astride the pressure roll by the weight of the carriage, a reversible motor mounted on the carriage and operatively connected with the driving rolls for rotating the same and rolling the pressure roll over the rug to be dried, wheels on one side of the carriage to prevent the same from tipping and to guide the carriage in a straight line across the platform, perforated pipes along the sides of the carriage for dispensing liquids upon the rug as the carriage is moved over the same, and means for controlling the supply of liquid through the pipes.

In testimony whereof I affix my signature.

ANDREW J. PEHL.
